UNITED STATES PATENT OFFICE.

OLMEDO CORTEZ WYSONG, OF GREENSBORO, NORTH CAROLINA.

ABRASIVE APPARATUS.

1,096,882.

Specification of Letters Patent.

Patented May 19, 1914.

Application filed April 23, 1912. Serial No. 692,651.

To all whom it may concern:

Be it known that I, OLMEDO CORTEZ WYSONG, a citizen of the United States, residing at Greensboro, in the county of Guilford and State of North Carolina, have invented certain new and useful Improvements in Abrasive Apparatus, of which the following is a specification.

My invention relates to improvements in abrasive apparatus.

One of its objects is to provide mechanism comprising one or more abrasive belts supported upon pulleys carried by standards adapted to be located any desired distance apart, and provided with means for adjusting the belt or belts relative to one of said standards to adjust both the upper and the lower reaches of the abrasive belt or belts to position for use by the operator.

Another object is to provide in connection with such apparatus an adjustable work supporting table adapted to be manipulated in conjunction with said belt or belts.

Another object is to provide improved means for adjusting one of the belt supporting pulleys both vertically and horizontally relative to its supporting standard.

My invention further consists in certain details of form, combination and arrangement, all of which will be more fully set forth in the description of the accompanying drawings, in which—

Figure 1 represents a side elevation of my improved mechanism. Fig. 2 is a perspective view of one of the belt supporting forms. Fig. 3 is a top plan view of the mechanism illustrated in Fig. 1. Figs. 4 and 5 are detail views of different belt supporting and shaping forms or supports. Fig. 6 is a side elevation of one of the belt supporting standards, being a section on line $\alpha-\alpha$ of Fig. 1. Fig. 7 is a side elevation of the opposite belt supporting standard, being a section on line $v-v$ of Fig. 1. Figs. 8 and 9 are detail views of different belt supporting and shaping forms or supports.

In the accompanying drawings illustrating the preferred embodiment of my invention, I have shown two abrasive belts A and A' mounted side by side upon driving pulleys 2 and 3 and idler pulleys 4 and 5. Where two belts are employed one is usually coated with coarse abrasive material and the other with fine abrasive material, one belt being used for the rough or

preliminary work, and the other for the final or polishing operation. A single broad belt upon single driving and idler pulleys may also be employed, depending upon the work to be treated.

The abrasive belt driving pulleys 2 and 3 are rigidly mounted upon a shaft 6 which is journaled upon a frame or standard B adapted to be bolted to the floor C. Tight and loose pulleys 7 and 8 at the opposite end of the shaft 6 provide for driving the shaft 6 by means of a belt 9 from a line shaft. A belt shifter 10 carried by the standard B enables the belt 9 to be shifted to control the movements of the shaft 6. A slotted cross-bar 11, preferably of wood is carried by a bracket 12 attached to the standard B, and the abrasive belts A A' travel through the slot in said cross-bar. Mounted upon the lower fork of the cross-bar 11 is a yoke-shaped bracket α , the eye of which is adapted to receive and vertically support a detachable pin or bar 13 interposed between the belts A A' to assist in holding said belts in place upon the driving pulleys 2, 3, and to prevent their interfering with each other.

The standard supporting the idler pulleys 4 and 5 comprises in connection with adjustable members mounted thereon, a base member D, which is adapted to be bolted to the floor C either close to or at a considerable distance from the standard B, depending upon the length of the abrasive belts, and the character of work chiefly required to be treated. Thus where a majority of the work to be treated is long pieces, long abrasive belts would be employed and the standards B, D located a considerable distance apart, while if the majority of the work was to be short pieces, short belts would be employed and the standards located closer to each other, which however would not interfere with the treatment of long pieces of work if required. Standards B, D, are thus capable of adjustment with the floor as a common supporting member, to and from each other as occasion may require. The lag screws or bolts holding said standards to the floor being readily removable for that purpose. The member D is provided with beveled ways at d to receive the downwardly projecting tongue or plate 14 of a vertically adjustable member E, which is also supported by a cylindrical slid-

ing member 15 seated in the bore of a post 16 forming part of the member D. Said hollow post 16 is slotted at 17 and adapted to be clamped upon the member 15 to lock the parts to adjusted position. A screw rod 19 seated in and engaging the threaded interior of a post or sleeve 18 forming part of the member D, provides for the vertical adjustment of the member 19 relative to member D. In order to rotate the screw 19 I provide a spiral gear 20 on said screw rod, which is in mesh with a spiral gear 21 on a shaft 22 carried in journals on the arm or bracket 23 of the member E, said shaft 22 being provided at its projecting end with a wrench seat to enable it to be turned to rotate the screw rod 19 and adjust the height of the member E. A wrench 24 is also provided for clamping the plate 14 to its adjusted position relative to the member D.

Substantially horizontal ways 25 are provided at the upper end of the member E, upon which ways is mounted an adjustable member F, which is adjustable relative to member E by means of a rack 26 carried by member F and a pinion 27 journaled by shaft 28 to member E and adapted to be turned by a hand wheel 29.

Mounted upon the member F, and pivotally connected thereto by means of a bolt 30 is a member H which is provided with journal boxes 31, 32 to support the shaft 33 of the idler pulleys 4 and 5. The pivotal movement of the member H relative to member F is limited by means of a bolt 34 passing through a curved slot in the member H and threaded into the member F, and which bolt serves to lock said members together when properly adjusted. A projection 35 on the member H enters between two ears 36, 37 projecting from member F, and is engaged upon opposite sides by thumb screws 39, 40 threaded through the ears 36, 37, by means of which the desired pivotal adjustment of the member H is accurately secured, and said thumb screws also assist in locking the member H to adjusted position. The member H is also supported by means of a link 41 pivoted to an ear 42 projecting from the member H and extensively or adjustably connected to the bracket 23 by means of bolts passing through slotted openings in the link 41, and adapted to clamp the link 41 to bracket 23 so as to support the overhanging portion of the member H after being adjusted to position.

The member H is also provided with standards 43, 44 carrying a shaft or rod 45. Pivotally mounted upon the rod 45 are arms 46, 47 at the free ends of which are rollers 48, 49 adapted to project between the upper and lower reaches of the respective belts A, A' and to engage or bear upon the inner faces of said belts either for the purpose of tensioning said belts or for tension-

ing and shaping said belts. Said rollers are pivotally mounted upon stud shafts 50 carried by the free ends of said arms 46 and 47, and are adapted to engage either the upper or lower reaches of said belts. Each of said arms 46, 47 is provided with an arm 51 provided with a counterweight 52 to hold the respective rollers in contact with the abrasive belts, said arms 51 being adjustable as indicated in Figs. 8 and 9 to press said rollers against either the upper or lower reach of the abrasive belts.

Slotted arms 53, 54 adjustably secured to the standards B, D are adapted to adjustably support at their free ends 55 either stationary forms e of the general character indicated in Figs. 2 and 5 or rotary forms f as indicated in Fig. 4 to either shape or tension the abrasive belts.

K represents the base of a work supporting table. L represent vertically adjustable members which are capable of being adjusted in unison by means of two screw rods 60 threaded to the members L and provided with beveled gears 61 meshing with beveled gears 62 on the horizontal shaft 63, which is adapted to be turned by the hand wheel 64. The members L are provided at their upper ends with pivotally connected cross rails 65 capable of adjustment to varying degrees of angularity by means of slotted segments 66. The table top M is provided with rollers 67 adapted to travel crosswise of the abrasive belts upon the tracks or rails 65, being limited by the stops 68 at the ends of the rails.

As illustrated in Fig. 1 the various parts are adjusted to receive the work upon the work table and between said table and the lower reaches of the abrasive belts, so that the belts travel normally slightly out of contact with the work, said belts being tensioned by the rollers 48 and 49. For treating plain or flat faced work the belts are straight in cross section as indicated in Figs. 6 and 7, while for treating work with curved or irregular faces, such as moldings for instance, the belts are shaped in cross section by means of rotary or stationary forms as indicated in Figs. 2, 4, and 8, to approximately the outline of the work to be treated. The belts are then by means of a form in the hand of the operator pressed into contact with the face of the work until it is sufficiently polished.

When it is desired to use the upper reach of the abrasive belts as indicated in Figs. 5 and 9, the work table M is either lowered away from the belts, or removed from beneath the belts, whereupon the member E is lowered until the upper reach of the belts adjacent to the idler pulleys 4 and 5 is low enough so that the operator can conveniently apply the work to the upper face thereof. Figs. 2 and 5 indicate a class of stationary

forms adapted to support and if desired shape the belts for polishing short articles such as chair backs, and drawer fronts, while Fig. 9 indicates an adjustment of parts for 5 polishing legs, spokes and other parts, in which the pressure of the work upon the belt between the roller 49 and the idler pulley 5 causes the belt to assume substantially the position indicated in dotted lines. The 10 pivotal adjustment of the member H relative to member F provides for alining the idler pulleys to cause the abrasive belts to travel centrally thereon, and the adjustment of the member F relative to member E 15 provides for securing the desired amount of slack in the abrasive belts. If desired the arms 46 and 47 may be supported upon independent stud shafts carried by the standards 43, 44 instead of through rod 45. It 20 will be noted that the member H overhangs the horizontally adjustable member F so that the idler pulleys 4, 5 are at one side of said member F, and that the driving pulleys are at one side of the standard B, which provides for placing very 25 long pieces of work upon the table M without contacting with or interfering with the mechanism or supports, even though the ends of the work project beyond the 30 driving or idler pulleys.

For ordinary purposes a single set of tensioning rollers 48, 49 and counterweights 52 carried as illustrated in Fig. 1 upon the vertically adjustable standard will be found to 35 answer all requirements. Said rollers or forms and their counterweights may however for certain classes of work be mounted upon the standard B. It is also advantageous under certain circumstances to simultaneously employ two duplicate sets of rollers 48, 49, or forms and counterweights 52, one set carried upon the standard D and the other set mounted upon the standard B.

Usually the floor to which the standards 40 B, D are attached will be found to give sufficient support to resist the tension of the sand belt tending to draw the driving and idler pulleys toward each other. For use if desired with unusually long or heavy belts, 45 or where the floor support is not sufficient, I preferably provide sockets 80 carried by the standards B, D to receive the ends of a rigid piece of timber or metal bar 81 cut to the required length, and which upon being 50 bolted in place serves in addition to the floor to retain the standards rigidly in place and the desired distance apart.

The mechanism herein illustrated and described is capable of considerable modification without departing from the principle 55 of my invention.

Having described my invention, what I claim is;

1. In a mechanism of the character described, an abrasive belt, a driving pulley

and an idler pulley to support and propel said belt, a standard to which said driving pulley is journaled, and an independent vertically adjustable standard to which said idler pulley is journaled, said standards being capable of independent attachment upon a common support to enable said standards to be set at different distances apart. 70

2. In a mechanism of the character described, an abrasive belt, a driving pulley 75 and an idler pulley to support and propel said belt, a standard to which said driving pulley is journaled, a vertically adjustable standard to which said idler pulley is journaled, and an independent vertically adjustable table beneath said belt, said standards being capable of independent attachment upon a common support. 80

3. In a mechanism of the character described, an abrasive belt, a driving pulley 85 and an idler pulley to support and propel said belt, a standard to which said driving pulley is journaled, and a standard to which said idler pulley is journaled said idler pulley standard comprising a base, a member vertically adjustable relative to said base, a member mounted upon said vertically adjustable member and adjustable relative thereto in a substantially horizontal direction and substantially in line with the 90 belt travel, and a member pivotally adjustable relative to said horizontally adjustable member, said pivotally adjustable member being provided with journal bearings to support said idler pulley. 95

4. In a mechanism of the character described, an abrasive belt, a driving pulley and an idler pulley to support and propel said belt, a standard to which said driving pulley is journaled, and a standard to which 105 said idler pulley is journaled, said idler pulley standard comprising a base, a member vertically adjustable relative to said base, a member mounted upon said vertically adjustable member and adjustable relative to said base 110 thereto in a substantially horizontal direction and substantially in line with the belt travel, and a member pivotally adjustable upon and relative to said horizontally adjustable member, said pivotally adjustable member being provided with journals to support said idler pulley and with means to yieldingly tension said abrasive belt. 115

5. In a mechanism of the character described, an abrasive belt, a driving pulley 120 and an idler pulley to support and propel said belt, a standard to which said driving pulley is journaled, a standard to which said idler pulley is journaled, said idler pulley standard comprising a base, a member vertically adjustable relative to said base, mechanism to positively adjust said vertically adjustable member, a member mounted upon said vertically adjustable member and adjustable relative thereto in a sub- 125 130

stantially horizontal direction and substantially in line with the belt travel, and a member carried by and pivotally adjustable relative to said horizontally adjustable member, said pivotally adjustable member being provided with journal bearings to support said idler pulley.

6. In a mechanism of the character described, an abrasive belt, a driving pulley and an idler pulley to support and propel said belt, a standard to which said driving pulley is journaled, and a standard to which said idler pulley is journaled, said idler pulley standard comprising a base, a member carried by and vertically adjustable relative to said base, a member mounted upon said vertically adjustable member and adjustable relative thereto in a substantially horizontal direction and substantially in line with the belt travel, mechanism to positively adjust said horizontally adjustable member and a member pivotally adjustable upon and relative to said horizontally adjustable member, said pivotally adjustable member being provided with journal bearings to support said idler pulley.

7. In a mechanism of the character described, an abrasive belt, a driving pulley and an idler pulley to support and propel said belt, a standard to which said driving pulley is journaled, and a standard to which said idler pulley is journaled, said idler pulley standard comprising a base, a member carried by and vertically adjustable relative to said base, a member mounted upon said vertically adjustable member and adjustable relative thereto in a substantially horizontal direction and substantially in line with the belt travel, and a member carried by and pivotally adjustable relative to said horizontally adjustable member, mechanism to positively adjust said pivotally adjustable member, and journal bearings carried by said pivotally adjustable member to support said idler pulley.

8. In a mechanism of the character described, an abrasive belt, a driving pulley and an idler pulley to support and propel said belt, a standard to which said driving pulley is journaled, and a standard to which said idler pulley is journaled, said idler pulley standard comprising a base, a member vertically adjustable relative to said base, a member mounted upon and pivotally adjustable relative to said vertically adjustable member, and provided with journal boxes to support said idler pulley, and a counterweighted abrasive belt tensioning member supported upon said pivotally adjustable member.

9. In a mechanism of the character described, an abrasive belt, a driving pulley and an idler pulley to support and propel said belt, a standard to which said driving pulley is journaled, and a standard to which

said idler pulley is journaled, said idler pulley standard comprising a base, a member vertically adjustable upon and relative to said base, a member mounted upon said vertically adjustable member and adjustable relative thereto in a substantially horizontal direction and substantially in line with the belt travel, and a member carried by and pivotally adjustable relative to said horizontally adjustable member overhanging said horizontally adjustable member and being provided with journal bearings to support said idler pulley at one side of said horizontally adjustable member.

10. In a mechanism of the character described, an abrasive belt, a driving pulley and an idler pulley to support and propel said belt, a standard to which said driving pulley is journaled, and a standard to which said idler pulley is journaled, said idler pulley standard comprising a base, a member carried by and vertically adjustable relative to said base, and a member mounted upon and pivotally adjustable relative to said vertically adjustable member and provided with journal boxes to support said idler pulley, said idler pulley being adjustable to bring either the upper or lower reach of said belt to operative position, and mechanism carried by said idler pulley standard to support a form in contact with the rear face of said belt.

11. In a mechanism of the character described, a plurality of substantially parallel abrasive belts, driving pulleys and idler pulleys to support and propel said belts, a standard to which said driving pulleys are journaled, and a standard to which said idler pulleys are journaled, said idler pulley standard comprising a base, a member carried by and vertically adjustable relative to said base, a member mounted upon and pivotally adjustable relative to said vertically adjustable member and provided with journal boxes to support said idler pulleys, and means to independently tension said respective belts.

12. In a mechanism of the character described, a plurality of adjacent and substantially parallel abrasive belts, driving pulleys and idler pulleys to support and propel said belts, a standard to which said driving pulleys are journaled, and a standard to which said idler pulleys are journaled, said idler pulley standard comprising a base, a member carried by and vertically adjustable relative to said base, a member mounted upon said vertically adjustable member and adjustable relative thereto in a substantially horizontal direction and substantially in line with the belt travel, a member carried by and pivotally adjustable relative to said horizontally adjustable member, said pivotally adjustable member being provided with

journal boxes to support said idler pulleys and means to independently tension said respective belts.

13. In a mechanism of the character described, an abrasive belt, a driving pulley and an idler pulley to support and propel said belt, a standard to which said driving pulley is journaled, a standard to which said idler pulley is journaled, said idler pulley standard comprising a base, a member vertically adjustable relative to said base, a member mounted upon and pivotally adjustable relative to said vertically adjustable member, and provided with journal boxes to support said idler pulley, and an abrasive belt tensioning member carried by one of said standards and engaging said belt and exerting a yielding tension thereon.

14. In a mechanism of the character described, an abrasive belt, a driving pulley and an idler pulley to support and propel said belt, a standard to which said driving pulley is journaled, a standard to which said idler pulley is journaled, said idler pulley standard comprising a base, a member vertically adjustable relative to said base, a member mounted upon vertically adjustable member and adjustable relative thereto in a substantially horizontal direction and substantially in line with the belt travel, and a member carried by and pivotally adjustable relative to said horizontally adjustable

member and provided with journal boxes to support said idler pulley, and an abrasive belt tensioning member carried by one of said standards and engaging said belt and exerting a yielding tension thereon.

15. In a mechanism of the character described, an abrasive belt, a driving pulley and an idler pulley to support and propel said belt, supporting members spaced the desired distance apart by means of a rigid connection, one of said pulleys being journaled to one of said supporting members, and the other supporting member being provided with a member adjustable transversely of the belt line and to which the other of said belt pulleys is journaled.

16. In a mechanism of the character described, an abrasive belt, a driving pulley and an idler pulley to support and propel said belt, standards spaced the desired distance apart by means of a rigid connection, one of said pulleys being journaled to one of said standards, and the other standard being provided with a vertically adjustable member to which the other of said pulleys is journaled.

In testimony whereof I have affixed my signature in presence of two witnesses.

OLMEDO CORTEZ WYSONG.
